UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

CULTIVATOR.

SPECIFICATION forming part of Letters Patent No. 794,796, dated July 18, 1905.

Application filed February 11, 1905. Serial No. 245,242.

To all whom it may concern:

Be it known that I, WILLIAM S. GRAHAM, a citizen of the United States, residing at Canton, in the county of Fulton and State of Illinois, have invented certain new and useful Improvements in Cultivators, of which the following is a specification.

My improvement relates to a cultivator, and especially to one comprising a gang of cultivator or shovel frames.

My object is to construct a machine employing a series or gang of cultivator or shovel frames such that the machine will be compact and simple in construction and so arranged that the gang of shovel-frames may be elevated or depressed simultaneously while permitting a single shovel-frame to be elevated or depressed independent of the gang or series. There is preferably shown a main operating or tension device comprising a strong spring which is put under tension by the depression of the shovel-frame so connected with the lifting mechanism that it will assist in lifting both the gang of shovel-frames and any individual shovel-frame and will also coöperate with the lifting mechanism to hold the shovel-frames in raised position.

Another feature consists in the connection between the shovel-frames and the lifting mechanism such that there is permitted a very fine adjustment when the shovels are in their depressed position regardless of lateral movement, while insuring that the shovel-frames may be lifted very high by a comparatively small movement of the lifting mechanism.

In the drawings, Figure 1 is a plan view of the machine. Fig. 2 is a side elevation. Fig. 3 is a detail view of the main operating-spring and its connection. Fig. 4 is a sectional view of the levers for lifting the shovel-frames. Fig. 5 is a detail view of the lifting mechanism, showing the parts with the shovel-frame in depressed position. Fig. 6 is a detail view of the lifting mechanism, showing the relative location of the parts when the shovel-frame is in elevated position. In Figs. 5 and 6 the parts are broken away. Fig. 7 is a perspective detail view.

Like letters of reference throughout the different views indicate similar parts.

In the drawings, the frame comprises two cross-bars A and B, Figs. 1 and 2. These cross-bars are connected by rails C, which converge at their forward ends (looking toward the front of the machine) and are connected to the tongue D. There are shown two tongues and two rails for each tongue, the rear end of each tongue being supported on the cross-bar B. It will thus be seen that this particular machine which I have illustrated is a three-horse machine.

The arches E are supported by the cross-bar B, and the arches constitute the frame to which the shovel-frames are pivoted in the usual manner, and, as particularly shown in Figs. 5 and 6, these arches are braced by braces connected with the tongue and cross-bars. As shown in Fig. 2, the arches F, which are supported by the cross-bar A, Figs. 1 and 2, constitute the axle for the carrying-wheels G. The shovel-frames α' are connected together by a coupler α^2 , Fig. 2, which coupler is supported by the cross-bar A. The shovels are indicated by the reference-letter α^3 . The lifting mechanism for the shovel-frames comprises a hand-lever for each shovel-frame, said hand-levers being indicated by reference-letters α^4 and α^5 , Figs. 1 and 2.

The seat H is supported from the frame of the machine, and on each side of the seat there projects a pair of levers which control a corresponding pair of shovel-frames. It will be only necessary to describe one pair of shovel-frames and associated parts, it being understood that the other pair are duplicates of the ones described.

The hand-levers α^4 and α^5 are pivoted to a bracket α^6 , Figs. 2, 5, and 6, which bracket is rigidly bolted to the cross-bar A. There is a segment-plate α^7 with notches formed on both upper sides of the same. This segment-plate, as shown in Fig. 4, is formed with a hub projecting from each side of the same, (indicated by reference-letter α^8 .) There are sockets α^9 formed in the ends of each hand-lever α^4 and α^5 , which bear against the hub α^8 . Said sock-

ets are cut away at the rear in the manner indicated at a^{10} . There are projections extending from said sockets (indicated by a^{11}) and a spring a^{12} , which connects the two hand-levers together. It will be apparent in the construction described that either one of the hand-levers may be moved laterally against the tension of the spring, the cut-away part a^{10} permitting lateral movement of the sockets a^9 about the head ends of the hub a^8 . The hand-levers are each formed with a tooth a^{13} , Figs. 3 and 4, and the tooth or lug of each hand-lever is adapted to engage in the notches a^{14} of the segment-plate a^7 . Consequently the tooth formed on each hand-lever is held in contact with the notches formed on the segment-plate by means of the spring a^{12} ; but each hand-lever, as heretofore explained, may be disconnected from the same by moving said hand-lever laterally against the tension of the spring, and after the hand-levers are disconnected from the segment-plate they may be oscillated back or forth independent of segment-plate a^7 for the purpose hereinafter described.

There are lugs a^{15} formed on the segment-plate which coöperate with the projections a^{11} , formed on the sockets of the hand-levers to arrest the movement of the hand-levers and prevent the same from moving past the notches formed on the segment. There is a bolt a^{16} which extends through the hub and segment-plate and through the ends of the sockets of the hand-levers and the bracket a^6 , thereby pivotally connecting said parts to said bracket. It is arranged that both the segment-plate and the hand-levers may be oscillated on the bolt a^{16} as a pivot. The socket a^9 of hand-lever a^5 is formed with a lug a^{17} , and a connecting-rod a^{18} is pivoted at one end to said lug a^{17} . Said rod is formed with a loop at the other end, a^{19} , and this loop connects with a pin formed on the crank-arm a^{20} , Figs. 1 and 3. This crank-arm is journaled loosely on the shaft a^{21} . In Figs. 1 and 3 this crank-arm a^{20} is shown formed with a lower arm, which is connected to a rod or link, which in turn is connected to the left-hand shovel-frame (looking toward the front of the machine) of the right-hand pair of shovel-frames, (indicated by a^{29}).

The shaft a^{21} , as seen in Fig. 1, extends partly across the frame of the machine and constitutes the connection between the lifting mechanism and the right-hand shovel-frame of said pair of shovel-frames. This shaft is supported by the rails C C and is journaled loosely in the bearings formed on said rail.

The hand-lever a^4 has its socket a^9 also formed with a lug a^{22} , Fig. 3, and there is a connecting-rod a^{23} pivoted to one end of said lug and formed with a loop a^{19} at the other end, which loop is connected to a crank-arm a^{24} , rigidly journaled on the shaft a^{21} . On the right-hand end of said shaft there is an

arm a^{25} , also rigidly journaled on said shaft a^{21} . This arm has a depending link a^{26} pivoted to the fore end of said arm, and said link is formed with a step a^{27} . The lower end of said link a^{26} is pivotally connected to a rod a^{28} , which is pivotally connected to the shovel-frame a' at a point indicated by reference-letter a^{29} . It is apparent, therefore, that whenever the crank-arm a^{24} is oscillated the shaft a^{21} is also oscillated in its bearings, which in turn oscillates the arm a^{25} . When the shovel-frame a' is in its lowermost or depressed position, as seen in Fig. 5, the step a^{27} will be out of contact with the projecting stop a^{30} , formed on the arm a^{25} , and consequently a slight movement of the arm a^{25} will cause only a slight movement of the shovel-frame; but when the arm a^{25} is elevated into the position shown in Fig. 6 the step a^{27} will contact against the stop a^{30} , and the link a^{26} and arm a^{25} will then become a compound lever, and a slight movement of the shaft a^{21} will transmit a comparatively great movement to the shovel-frame a' by reason of the increased leverage.

As will be seen from Fig. 2, the connecting-rod a^{28} is pivoted to arm a^{25} at a point substantially directly above the center about which shovel-frame a' is swung. Consequently the shovel-frame may be moved laterally when in working position without affecting the depth at which the shovel will work nor interfering with the fine adjustment provided for by the step a^{27} . By this construction I can use short levers a^4 and a^5 , located closely to the operator, capable of effecting a very fine adjustment of the shovel-frame by a comparatively short movement thereof.

Referring to Figs. 5 and 6, I have shown the segment-plate a^7 formed with a tailpiece a^{31} . To this tailpiece there is pivoted a link a^{32} , which in turn is pivoted to the upper end of the crank-arm a^{33} , which crank-arm is pivoted near its center to the bracket a^6 and is connected at its lower end to the spring a^{34} , which constitutes the main operating spring or device of my machine. The crank-arm a^{33} is formed with a hook projection a^{35} , which in normal position, as shown in Fig. 5, is adapted to contact against the tailpiece a^{31} , and it is readily seen that in this position the contractile force of the spring a^{34} tends to hold the segment-plate a^7 against upward movement, and thereby tends to hold it in its depressed position, the said segment-plate being shown in Fig. 5 in elevated position and in Fig. 6 in depressed position. When the shovel-frames are depressed and the segment-plate is moved to its elevated position, (shown in Fig. 5,) the main operating-spring a^{34} is put under increased tension. The inner end of the spring a^{34} , which is the main operating device, is connected to a screw-fitted bolt a^{36} , and this bolt extends through a connecting-arm a^{37} , Figs. 1 and 3, which is supported at

each end in bearings formed in the crank-arms a^{21} and a^{20} . In this way the spring is at its inner end connected to both hand-levers by reason of its connection with the arm a^{37} , 5 which in turn is connected at its ends with the crank-arms a^{21} and a^{20} .

The tail of the segment-plate a^{31} is formed with the projecting stop a^{41} , and said stop when the lever is in elevated position bears 10 against the bracket a^6 , as shown in Fig. 5, and in this position the tension of the spring a^{34} holds the stop a^{41} against the bracket by reason of the toggle formed by the pivots of the links a^{32} and the lever a^{34} falling approximately into line, thereby holding the hand-levers and segment-plate in elevated position in the lowermost position of the shovel. The frame is held partly in place by the toggle by reason of the force of the spring a^{34} being 20 transmitted through the arm a^{35} and the link a^{32} and extending downwardly on the stop a^{31} , so as to hold it in engagement with the frame. 25

It will be evident that by reason of the loops a^{19} and their connections with the shovel-frames the shovel-frames can be lifted independent of the connecting-rod a^{23} and a^{18} . By this construction obstructions on the ground in which the shovels are working may 30 raise the shovel-frames without in any way affecting the hand-levers and segment-plate. It will also be apparent that the main operating-spring a^{34} , as shown in Fig. 6, tends to assist to oscillate the shaft a^{21} , and thereby assists in raising the shovel-frames connected 35 therewith and in holding the same in raised position. The connections between the spring a^{34} and each hand-lever are such that there is a limited amount of movement in the ends of the arm a^{31} within the bearings formed in the 40 crank-arm a^{21} and a^{20} , so that each hand-lever can be moved independent of the other, and the spring a^{34} will assist in the raising of any shovel-frame and in the holding of the same in its elevated position.

45 It is apparent that if neither one of the hand-levers is moved laterally and disconnected from the common segment-plate the movement of one hand-lever will move the segment-plate and the motion will be transmitted to the other one of the hand-levers, so that the gang or pair of shovel-frames will be moved simultaneously. From the description 50 it will be seen that in the position shown in Fig. 6 the tension of the main operating-spring a^{34} will be through the hooked end a^{35} and the tail a^{31} of the segment-plate, and the effective force of this spring will hold the segment-plate and the hand-lever connected therewith in their depressed position, where- 55 as in the position of parts shown in Fig. 5 the tension of the main spring a^{34} will be through the link a^{32} , causing the stop a^{41} to bear down against the bracket a^6 , and thus tend to hold the segment-plate and operating-levers in their depressed position.

In the position of parts shown in Fig. 5, as heretofore explained, the tension-spring a^{34} will operate on the segment-plate in such manner as to coöperate with the stop a^{41} to hold said levers in elevated position and hold 70 the segment-plate against movement, while in Fig. 6 the parts are shown moved to a position such that the spring a^{34} will act as a counterbalance to the weight of the shovel-frames, since the weight of the shovel-frames 75 will tend to elevate the controlling-levers and oscillate the segment-plate, whereas the tension of the spring will tend to hold the controlling-levers and plate against such movement. 80

Having thus described my invention, I claim—

1. In a cultivator, the combination of a gang of shovel-frames with a main operating device, means for raising said gang of shovel-frames, 85 and means for raising independently each individual shovel-frame, and connections with the main operating-spring whereby said operating device will coöperate to assist in raising said gang, and in raising each individual shovel-frame, for the purpose specified.

2. In a cultivator, the combination of a gang of shovel-frames with a main operating device, controlling-levers connected to said shovel-frames, connections from said operating device to said levers, and means for automatically holding said levers both in raised and lowered position by the tension of said operating device, substantially as specified. 95

3. In a cultivator, the combination of the 100 shovel-frames, means for elevating and depressing said shovel-frames, a main operating device, and a stop device for said elevating means coöperating with said main operating device to hold said elevating means against 105 movement when in elevated position, and means for counterbalancing the force exerted by said frames on said levers, substantially as described.

4. In a cultivator, the combination of a 110 shovel-frame, means for elevating and depressing said shovel-frame, a movable stop device, and connections between said stop device and said elevating means whereby the main operating device will hold said stop 115 against the frame of said cultivator when the shovel-frames are in normal or depressed position and connections between the main operating device and the elevating means for automatically holding the elevating means 120 against movement in the elevated position of the frames by the tension of the main operating device, substantially as described.

5. In a cultivator, the combination of a 125 shovel-frame with a lever for elevating and depressing the same, connections between said lever and said shovel-frame, comprising a plurality of arms, one of said arms being formed with a step, and another with a projection adapted to bear against said step, means for 130

raising said frame a predetermined distance prior to the contact of said projection against said step, for the purpose specified.

6. In a cultivator, the combination of a plurality of shovel-frames, a universal-joint connection between said shovel-frames and cultivator-frame, controlling-levers for elevating and depressing said shovel-frames, and a connecting-rod pivoted at its lower end to said shovel-frame independent of said universal joint and a member common to said shovel-frames connected to the upper ends of said connecting-rods substantially in a direct line above said joint, for the purpose specified.
- 15 7. In a cultivator, the combination of a plurality of levers and a plurality of shovel-frames, a single segment for both of said levers, a main operating device connected to said segment, and also connected to each of said levers, independent of said segment, connections from each of said levers to a shovel-frame, for the purpose specified.

8. In a cultivator, the combination of a plurality of levers, a movable segment device, 25 a plurality of shovel-frames, connections between said shovel-frames and said movable segment device, a main operating device put under tension by said shovel-frame, and means for automatically holding said movable segment against movement by the tension of said main operating device when said frames are in the elevated position, for the purpose specified.

9. In a cultivator, the combination of controlling-levers with shovel-frames connected therewith, a main operating device, connections between controlling-levers and said operating device for holding said levers against movement when said frames are in depressed position and for counterbalancing said frames when in elevated position, for the purpose specified.

10. In a cultivator, the combination of the controlling-levers, shovel-frames connected therewith, a main spring, connections from said main spring to said levers comprising movable arms, and means for moving said arms whereby same will coöperate with said main operating-spring to hold said levers 45 against movement when said frames are in depressed position and to counterbalance the weight of said frames when same are in elevated position.

11. In a cultivator, the combination with 55 controlling-levers, shovel-frames connected therewith, a main operating device, a movable stop device, connections from said main operating device to said levers comprising movable arms adapted to coöperate with said main 60 frame whereby said main operating device

will hold said stop device against the cultivator-frame when the shovel-frames are in depressed position and will counterbalance the weight of said frames when same are in elevated position, for the purpose specified.

12. In a cultivator, the combination with a plurality of controlling-levers, a segment-plate common to two of said levers, means for holding said levers in engagement therewith, means for moving any one of said levers laterally for the purpose of disconnecting same from said segment-plate, shovel-frames, and connections from said shovel-frames to said levers, a main operating device, and connections comprising movable arms between said main operating device and said segment-plate whereby said main operating device will hold said segment-plate against movement when said frames are in depressed position and will assist in counterbalancing the weight of said frames when same are in elevated position, substantially as described.

13. In a cultivator, the combination of shovel-frames movable laterally with controlling-levers for elevating and depressing the same, connections between said frame and said levers, including a connecting-rod, pivoted to the shovel-frames, the arc of lateral movement of said frames being in the same horizontal plane and substantially equidistant from the center about which the said connecting-rod swings, for the purpose specified.

14. In a cultivator, the combination of shovel-frames with controlling-levers, connections between said levers and said shovel-frames, comprising pivoted connecting-rods and a plurality of arms connected to said rods, which arms are arranged to move independently during the preliminary raising of said shovels, but adapted to form a compound lever during further movement, said connecting-rods being pivoted to one of said arms, the pivotal point thereof being substantially in line with the axis of movement of the shovel-frame, and perpendicular to the horizontal plane of said frame, for the purpose specified.

15. In a cultivator, the combination of a plurality of shovel-frames with a plurality of controlling-levers, connections between each pair of levers, a main operating device connected at one end to a pair of shovel-frames and at the opposite end to the connections for the controlling-levers, for the purpose specified.

In testimony whereof I have hereunto set my hand this 6th day of February, A. D. 1905.

WILLIAM S. GRAHAM.
